Inventor
Kirk

Gilbert A. Newkirk.

Attorney

UNITED STATES PATENT OFFICE.

GILBERT A. NEWKIRK, OF DENVER, COLORADO.

LIFE-INSURANCE-COMPUTING PACKET.

1,314,146.

Specification of Letters Patent. Patented Aug. 26, 1919.

Application filed June 19, 1916. Serial No. 104,450.

To all whom it may concern:

Be it known that I, GILBERT A. NEWKIRK, a citizen of the United States, residing at the city and county of Denver and State of Colorado, have invented certain new and useful Improvements in Life-Insurance-Computing Packets; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to means for readily ascertaining the amount to be paid the beneficiary under a life insurance policy for a given amount of premium paid for any desired age of the insured, whether the policy be what is known as straight life or a policy calling for a certain amount payable to the beneficiary or the insured after a certain number of premium payments have been made.

In order to present the scheme in the form of an application for patent, I have illustrated in the drawing a packet based on an age of 35 years for the insured, one side of the packet being adapted for use where the policy is a 20 payment life, while the other side is for use where the policy is straight life, the age assumed being 35 years in each instance.

The packet consists of an envelop in which is slidably arranged a sheet, the envelop and the said sheet both having columns of figures, the items of which are respectively arranged in alinement, the items in any line having a certain relation to each other. For instance, when the packet is in one position and the sheet is drawn out of the envelop, the sheet contains a number of columns of items which is also true of the corresponding side of the envelop. The top line of items of the sheet, shows in the extreme left-hand column a certain premium payment, while in the same line on the envelop are found in the extreme left-hand column, the amounts payable monthly to the beneficiary for 20 years after the death of the insured. The corresponding item in the next right-hand column on the envelop contains the yearly amount paid the beneficiary; while the corresponding item of the next column toward

the right, indicates the total amount paid the beneficiary in 20 years.

The top item of the next column of the sheet toward the right shows the amount of the policy or the total cash which the beneficiary may receive at the time of the death of the insured corresponding with the amount of annual premium indicated in the adjacent left-hand column. The top item of the next column on the sheet toward the right, shows the amount of the policy or the cash payable under the policy to the beneficiary at the time of the death of the insured, assuming that the latter has paid an annual premium indicated by the top item of the next column toward the right. Finally, the top item of the extreme right-hand column of the sheet, indicates the amount of cash payable to the beneficiary at the time of the death of the insured, in addition to the monthly payment indicated by the top item of the extreme left-hand column on the envelop.

Assuming that the packet is in position to disclose the aforesaid information relating to a straight life policy, if it be turned a half revolution, or a half turn endwise in either direction, it will be in position to disclose the corresponding information for a 20 payment life policy, the items on the envelop in either case being the same, while the items on the sheet are different so far as the annual premium payments are concerned.

Having briefly outlined my improved packet, I will proceed to describe the same in detail, reference being made to the accompanying drawing, in which is illustrated an embodiment thereof. In this drawing—

Figure 1 is a view showing one side of my improved packet, the sheet being located within the envelop.

Fig. 2 is a view of one side of the sheet.

Fig. 3 is a section taken through the packet on the line 3—3, Fig. 1.

Fig. 4 is a view of the opposite side of the packet with the sheet partly removed.

Fig. 5 is a view of the sheet showing the reverse side from that disclosed in Fig. 2.

The same reference characters indicate the same parts in all the views.

Let the numeral 5 designate the envelop which is open on its left-hand edge 6 but closed at both ends as shown at 7 and 8 and on its opposite edge as shown at 9 except

that it is notched as shown at 10 to disclose a small part 12 of the sheet, in order to enable the user to move the sheet partly out of the envelop at its open edge or far enough 5 to allow the user to grasp a small projection 13 formed on the left-hand edge of the sheet and upon the opposite sides of which is found the number 35 to indicate the age of the insured, while on one side of the said 10 projection adjacent the number 35 is also found the number 20 to indicate that the information on that side of the sheet and the corresponding side of the envelop, relates to a 20 payment policy.

15 Referring now to the matter disclosed in Fig. 1, the side of the envelop there disclosed contains three columns which are designated by the letters *a*, *b* and *c*, respectively. The column *a* has in addition to the letter and in a space at the top of the column of figures, the words "Monthly income". The column *b* has in a corresponding position at the top of the column the words "Yearly income amounts to"; while the column *c* has in a corresponding position "In 20 years amounting to". The items in the column *a* below the caption indicate respectively the monthly income payable to the beneficiary at the death of the insured 25 for corresponding annual premium payments or deposits indicated in the extreme left-hand column designated *d* of the side of the sheet shown in Fig. 2. The figures below the caption in the column *b* of the envelop indicate the yearly income payable the insured corresponding to the monthly income indicated by the corresponding items in column *a*; while the items below the caption in column *c*, indicate the total 30 amount payable to the beneficiary in 20 years corresponding with the oppositely located items in the columns *a* and *b*.

The columns of the face 15 of the sheet are respectively designated reading from the 45 left toward the right, *d*, *g*, *g*, *d*, *f*. The items in the extreme left-hand column *d*, as heretofore indicated, designate the amounts of annual deposits or premium payments corresponding with the income items of the 50 columns *a*, *b* and *c* of the envelop whether on one side or the other, as the columns on both sides of the envelop are designated the same and the corresponding items of these columns are identical. The second column on the face 15 of the sheet reading from the left, being one of the columns designated *g*, contains amounts of policies corresponding to the premium items in the extreme left-hand column *d* of the sheet. 55 These policy items are the amounts which the beneficiary may receive in cash at the time of the death of the insured in lieu of the monthly income indicated by the items in the columns *a*, *b* and *c* of the envelop. 60 The third column counting from the left on 65

the face 15 of the sheet, shows the amounts payable to the beneficiary in cash at the death of the insured for the corresponding yearly premiums indicated in the next column toward the right, being another *d* column 70 and having the caption "Life annual premiums". The extreme right-hand column on the face 15 of the sheet, being the column designated *f* and having the caption "Amount paid immediately", shows the 75 amount payable to the beneficiary immediately upon the death of the insured for the corresponding premium payments indicated in the next column toward the left, in addition to the monthly payments indicated 80 in the column *a* of the envelop.

On the lower part of the envelop on each face 85 are data referring to the columns *a*, *b* and *c*; while on the lower part of the sheet on either face are explanatory data referring 90 to the matter found on the sheet. It should be stated that the captions of the columns on face 15 of the sheet (see Fig. 2) reading from the left toward the right (in addition to the letter designations heretofore stated) 95 are respectively as follows: "L Annual deposits"; "Amount of policy"; "If policy be for"; "Life annual premium (d)"; "Amount paid immediately (f)".

Referring now to Figs. 4 and 5, Fig. 4 95 shows the sheet partly removed from the envelop with two columns of its face 16 exposed. This face 16 of the sheet has five columns respectively designated by the following captions reading from the left toward the right: "20 Annual deposits (d)"; "Amount of policy (g)"; "If policy be for (g)"; "Life 20 annual premiums (d)"; "Amount paid immediately (f)". I will for convenience refer to these columns reading 100 from left toward the right respectively, by the reference numerals 17, 18, 19, 20 and 21. The items of column 17 are the amounts of 105 annual premiums paid or annual deposits made by the insured in order to entitle the beneficiary to the income instalment indicated by the corresponding items of the columns of the envelop; or to the cash indicated by the corresponding items in column 18 of the sheet; while the items of column 20 of 110 the sheet indicate the premiums paid by the insured in order to allow the beneficiary the instalment income indicated in the columns of the envelop; or the cash income indicated by the items in column 19 of the sheet. 115 Again, the column 21 of the sheet is the same as the extreme right-hand column of the face 15 of the sheet, and its items indicate the cash payments payable to the beneficiary at the death of the insured in addition to the instalments indicated in the extreme left-hand column of the envelop. 120

The foregoing explanation is believed sufficient when taken in connection with the explanatory matter on the lower parts of the 130

sheet and envelop. It should be stated that the envelop when held in position for either of the aforesaid uses, has the word "Guaranteed" at the top and immediately above the 5 income columns heretofore described.

Having thus described my invention, what I claim is,—

1. A computation device for an insurance policy including an envelop open on one 10 edge and having tabulated data pertaining to incomes to be derived from the policy on its opposite faces, and a sheet slidable in the envelop and having tabulated premiums on its opposite faces, the corresponding 15 incomes and premiums of the envelop and sheet being in transverse alinement as the sheet is moved out of the envelop to expose its tabulations, the sheet having a projection on its front edge and provided with data indicating the nature of the policy, the combined width of the projection and sheet being less than the width of the envelop so that the envelop protects the projection, and a notch at the folded edge of the envelop.
2. A computation device for an insurance 25 policy including an envelop open on one edge the opposite faces of which contain tabulated records of a plurality of incomes to be derived from the policy, and a sheet 30 slidable in the envelop and having a plurality of tabulated premiums on its opposite faces, the corresponding incomes and premiums of the envelop and sheet being in transverse alinement as the sheet is moved 35 out of the envelop to expose its tabulations, the sheet having a projection on its front edge and data on opposite faces of the pro-

jection indicating the nature of the policy for which the premiums of the sheet and incomes of the envelop are to be computed. 40

3. A computation device for an insurance policy including an envelop open on one edge, the opposite faces of which contain tabulated indicia of incomes due at fixed intervals of time, and a sheet slidable 45 in the envelop and having on its opposite sides tabulated indicia indicating different premiums, to be paid from time to time, the corresponding incomes and premiums of the envelop and sheet being in transverse alinement 50 as the sheet is moved out of the envelop to expose its tabulations, the sheet having a projection on its front edge and data on opposite faces of the projection indicating the nature of the policy for which 55 the premiums and incomes are to be computed.

4. A computation device including an envelop open on one edge and having data thereon, and a sheet slidable in the envelop 60 and having data thereon related to the data on the envelop, the sheet having a projection thereon bearing indicia related to said data, the width of the envelop being as great as the combined width of the projection and 65 sheet so that the envelop will protect the projection, the parts being formed so that the sheet may be moved from the envelop.

In testimony whereof I affix my signature, in presence of two witnesses.

GILBERT A. NEWKIRK.
